CLAIM

The ornamental design for a probe for aspirating and dispensing sample fluid in a clinical chemistry analyzer, substantially as shown and described.

DESCRIPTION

FIG. 1 is a top perspective view of a probe for aspirating and dispensing sample fluid in a clinical chemistry analyzer showing my new design;

FIG. 2 is a top plan view thereof;

FIG. 3 is a bottom plan view thereof;

FIG. 4 is a right side elevational view thereof;

FIG. 5 is a front elevational view thereof;

FIG. 6 is a left side elevational view thereof; and

FIG. 7 is a rear elevational view thereof.

FIG. 3FIG. 2FIG. 4FIG. 1FIG. 5FIG. 6FIG. 7
